UNITED STATES PATENT OFFICE.

HENRY M. LANE, OF DETROIT, MICHIGAN.

TRACK-SUPPORT FOR OVERHEAD CRANES.

1,332,627.

Specification of Letters Patent.

Patented Mar. 2, 1920.

Application filed April 17, 1919. Serial No. 290,854.

To all whom it may concern:

Be it known that I, HENRY M. LANE, a citizen of the United States, residing at Detroit, in the county of Wayne and State 5 of Michigan, have invented certain new and useful Improvements in Track-Supports for Overhead Cranes, of which the following is a specification.

This invention relates to improvements in 10 track supports for overhead cranes and it comprises an overhead railway consisting of vertical supporting members, horizontal members secured to said vertical members, track supporting means carried by said horizontal members and bracing means secured to said horizontal members and to said vertical members; and more specifically the invention consists of a foundry building or other structure having vertical supporting 15 members to support the roof and the side walls and a plurality of horizontal members secured to said vertical supporting members, diagonal bracing means secured to the vertical supporting members and to the horizontal 20 members and a second set of horizontal members arranged at right angles to the first mentioned horizontal members and forming a support for a rail, in combination with a underslung crane having a bridge extending substantially to the vertical members; all as more fully hereinafter set forth 25 and as claimed.

In the present method of constructing supports for overhead traveling cranes in 30 foundries and buildings of similar character, it is customary to support the track directly upon the vertical members which carry the roof and support the side walls of the building. Such a construction places a 35 great strain upon these supporting members and it is necessary to construct them of very heavy material to withstand such strains. In the usual layout of foundries, the building is divided into spaces termed "bays." 40 A crane is arranged in each bay and travels from end to end. The crane carries a trolley which may be moved on the bridge of the crane across the bay, but no means are provided for transferring a trolley from one 45 bay to another.

In the present invention I have produced a method of constructing foundries and buildings of this character wherein the overhead tracks for the crane are indirectly supported from the vertical supporting members by a truss brace or the like thereby re-

ducing the strain upon the vertical members. In a construction of this character much lighter material may be employed in the vertical members reducing the cost of 60 construction. In the present invention I also provide means for transferring a trolley from the traveling bridge of one crane to the bridge of the crane in the next bay permitting the trolley to be run to any point 65 within the building.

In the present construction I employ a crane of the underslung type traveling on tracks supported on a horizontal runway. The track runway or support is positioned 70 at considerable distance from the vertical columns which form the roof support of the building. This permits the framing in of a brace structure between said vertical columns and crane runway carrying the load to 75 a panel point in a truss brace arranged above the track support. I also employ a vertical latticed brace structure to bring the strains from the track or runway into the vertical column through a series of closed triangles 80 so as to eliminate serious turning or bending movement in the column.

In the accompanying drawings I have shown an advantageous embodiment of this invention.

Figure 1 is an end elevation of a foundry or other building consisting of three bays;

Fig. 2 is an enlarged detailed view, partly in section and taken in the same plane as Fig. 1 and

Fig. 3 is a horizontal sectional view on the line 3—3 of Fig. 2.

Referring to the drawings the reference numeral 1 designates the vertical supporting members or columns which support the 95 roof 2 of the building. Suitably arranged upon the columns is a series of channel irons to which are secured the transverse horizontal members 4. The transverse members form a support for longitudinal 100 members 5 which support the tracks 6. Suitable bracing means are provided for distributing the load and supporting the horizontal members. As shown, the bracing means consists of a truss comprising 105 horizontal members 7 arranged above the members (4) vertical members 8 and diagonal bracing members 9. The bracing members are arranged between the supporting columns and the track and similar 110 bracing means are arranged above the track consisting of horizontal members 10 ex-

tending from one column to the next column, vertical members 11 arranged between horizontal members (10) and the roof and diagonal members 12.

5 The crane consists of an axle 13, wheels 14 and brackets 15. The brackets carry the bridge 16 which is arranged below the tracks, and, as shown, extends beyond the plane of the wheels and substantially to 10 the vertical columns. Trolley 17 travels on the bridge and carries the load 18. The trolley may be power operated or hand operated.

15 The means for transferring a trolley from one bay to another consists of a cross over rail 19 arranged in the same horizontal plane with the traveling bridges of the cranes. A trolley may be transferred from one bay to the next by alining the traveling bridges with the cross over rail and running the trolley over the cross over rail 20 into the adjacent bay.

25 In Fig. 3 of the drawings I have shown bracing means arranged in a horizontal plane between a pair of adjacent transverse horizontal members (4). As shown, the bracing means consists of a pair of diagonally arranged rods 20 secured to the opposite ends of the members 4. The rods 30 may be threaded (not shown) to permit adjustment.

35 In the present construction I have produced a means for supporting overhead rails for cranes wherein the tracks are spaced from the vertical columns and supported by suitable panel bracing. It is evident that such a construction produces a rail supporting means in which the strain upon the vertical columns is materially lessened and therefore permits the use of 40 lighter materials in the construction of the vertical columns.

What I claim is:

45 1. In combination with a building construction comprising a roof and side walls, and vertical supporting members for said roof and side walls, of an overhead railway comprising a horizontal runway for the track, said horizontal runway being located 50 at a distance from said vertical supporting members, bracing means arranged between the horizontal runway and said vertical supporting members, and a truss brace arranged above said means extending from 55 the vertical supporting column on one side to the vertical supporting column on the opposite side, whereby the strains are carried to a panel point in the truss above and thence distributed to the vertical columns.

60 2. In combination with a building construction comprising a roof and side walls, and vertical supporting members for said

65 roof and side walls, of an overhead railway comprising a horizontal runway for the track, said horizontal runway being located 70 at a distance from said vertical supporting members, bracing means arranged between the horizontal runway and said vertical supporting members, and a truss brace arranged above the track runway, a series of 75 brace structures comprising horizontal members, vertical members, and a diagonal brace arranged between the vertical supporting members and the track runway whereby the track is suspended from a panel point in the truss, and the load is distributed by said second mentioned bracing means to reduce turning or bending in the columns.

80 3. In combination with a building construction comprising a roof and side walls, and vertical supporting members for said roof and side walls, of an overhead railway comprising a horizontal runway for the track, said horizontal runway being located 85 at a distance from said vertical supporting members, bracing means arranged between the horizontal runway and said vertical supporting members, and a truss brace arranged above said track runway between 90 each pair of vertical supporting members, a framed bracing structure arranged beneath the truss between the track runway and the vertical supporting members, the track runway being supported from said truss, and 95 the load distributed by said framed brace structure to said vertical columns.

4. In combination with a building construction comprising a roof and side walls, vertical supporting members for said roof and side walls, of an overhead railway comprising horizontal beams spaced and supported from said vertical supporting members, track supporting means carried by said horizontal members, bracing means arranged between said vertical supporting members and said horizontal beams, a track arranged upon said horizontal members, supporting means and an overhead crane adapted to travel on said track.

105 5. An overhead railway system comprising 110 two or more sets of parallel tracks, traveling cranes arranged to travel on said tracks, each of said cranes being provided with a traveling bridge to permit a trolley 115 to be carried by said crane, and cross-over rails arranged between said sets of tracks whereby said traveling bridges may be alined with the cross-over rail and the trolley transferred from one crane to another.

120 In testimony whereof, I affix my signature hereto.

HENRY M. LANE.
